FUEL FEEDING MEANS FOR INTERNAL
COMBUSTION ENGINES

Carl Herman Clausen, Stockholm, Sweden

Application September 22, 1937, Serial No. 165,219
In Sweden September 18, 1936

16 Claims. (Cl. 123—139)

The present invention refers to an improvement in fuel feeding means for internal combustion engines acting with direct fuel injection, and in which the fuel oil is pumped into a pressure piping connected with the valve-controlled injection nozzle of the engine.

In connection with similar fuel feeding means, and for prevention of so called after-dripping through the nozzle and the drawbacks resulting from such occurrences, it has previously been proposed automatically to perform a sudden decrease of pressure within the pressure piping, for instance by a discharge of fuel oil from, or an increase of volume of the said pipe. All of the means hitherto known for such purpose involve the drawback, however, that they do not at all, or in any case rather defectively only, adapt themselves according to the variable pressure conditions prevailing in the piping between the fuel pump and the valve-controlled injection nozzle, and therefore the efficiency of said known means will be more or less illusory.

The pressure at hand within the pressure piping during the injection is mainly a function of the dimensions of said piping, the velocity of the flow of fuel transmitted thereby, and the resistance of the injection nozzle valve itself, such resistance being composed by the resistance to the flow through the nozzle bores and that of the spring acting on the nozzle valve member. These factors are highly variable both in different engines and also in one and the same engine under different working conditions, and as a result hereof the pressure tending to re-open the nozzle valve and thereby to cause the after-dripping due to the pressure wave arising within the pressure piping after interruption of each separate fuel injection is also highly variable. Hence, a means for automatic decrease of pressure within the pressure piping after interruption of each fuel injection shall also automatically adapt itself to the different pressures which may arise in the piping.

According to the invention this result is obtained by the provision of a movable control member which is permanently acted upon by the pressure piping pressure for movement in one direction and adapted at its movement caused by said pressure, which movement consequently is controlled thereby in respect of velocity and causes an increase of volume of and a decrease of pressure within the pressure piping, to open a return channel from the pressure chamber of the fuel pump to a convenient low pressure cavity, or space, so that the interruption of the discharge

of fuel from the pump into the pressure piping and consequently the magnitude of the pressure decrease within the latter are automatically adapted to different pressure conditions within the pressure piping.

An embodiment of the invention is illustrated in the accompanying drawing to which the following description refers, and in this drawing—

Fig. 1 shows the improved fuel feeding means seen in axial section.

Fig. 2 shows a flattened out portion of the inner face of the fuel pump cylinder.

A pump piston 2 is reciprocably mounted within the cylinder 1 of the fuel pump, such piston being provided exteriorly with a circumferential recess positioned at a distance below the top face 7 of the piston and is confined at its upper portion by an inclined control edge 3. In the drawing, the pump piston is shown in its lower end position. Its upper end position is indicated by the dot and dash line X, and a little previous to the arrival of the piston into this last mentioned position during its upward stroke, the circumferential recess 4 establishes connection between the two bores or channel means 5 and 6. The pump piston is both reciprocable, as aforesaid, and turnable around its axis (manually or by means of governor), and a turning of the same in the direction of the arrow in the drawing will cause the control edge 3 to establish the connection between the bores 5 and 6 more and more early during the upward stroke of the piston, and finally to make such connection permanent. The reference letter 10 represents the pressure chamber of the pump, and this chamber is periodically in connection with a suction bore 8 and with an other bore 9.

A pressure valve 11 is mounted in the extension of the pump pressure chamber 10, this valve being preferably but not necessarily acted upon by a closing spring means 12. The cavity 13 enclosing said spring 12, and a bore 14 communicating with the former, form the entrance end of the pressure piping leading to the valve-controlled injection nozzle (not shown).

A piston-shaped control member 16 is reciprocably mounted within a cylinder bore 15 positioned at one side of the pump cylinder 1. The upper end of the bore 15 stands in permanent connection with the pressure piping 13, 14 by means of a bore 17 in the pressure valve housing 22, so that the control member is permanently acted upon by the pressure within said piping, whereas the lower end of the bore 15 stands in permanent connection with the channel means 5.

Assuming that the pressure chamber 10 is filled with fuel oil from the suction bore 8, and that the piston 2 is moving upwardly from the lower end position shown, for instance by being 5 acted upon by a cam disc, the fuel oil will at first be pressed back through the suction bore 8 until the top face 7 of the pump piston has moved upwards past the said suction bore and closed the same. Then follows a compression of the oil 10 within the chamber 10, and thereafter the oil will flow through the bore 9, a bore 18 connected with the upper portion of the chamber 10, an annular exterior recess 19 in the control member 16, and through bores 20 in the said member 15 into the channel means 5 and the circumferential recess 4 which latter at this moment is shut off 15 from the return bore 6. Due to the increase of the confined pressure caused by the continued upward travel of the pump piston, the control member 16 will move upwardly in the bore 15, and the pressure within the pressure piping 13, 14 will be increased thereby.

The upward travel of the control member 16 will be limited either when the top face 7 of the 25 pump piston moves past the bore 9 and closes the latter, or alternatively when the portion 21 of the member 16 positioned beneath the annular recess 19 closes the bore 18. In case the volume 30 of fuel oil answering to the distance of travel of the pump piston 2 previous to the closing of the bore 9 is greater than the volume answering to the travel of the control member 16 for closing of the bore 18, the first alternative comes true, but otherwise the second mentioned alternative is valid. In the first mentioned instance, the upward stroke of the member 16 could also be limited by the abutment of said member for instance against the upper end face of the cylinder bore 15, under the provision only that the 40 volume of fuel oil, which is discharged by the pump previous to the closing of the bore 9, is sufficiently great, and this is dependent on the level of the bore 9 in relation to the level of the suction bore 8.

It would apparently be possible entirely to leave 45 out the bore 9 as far as the effectuation of the movement of the member 16 is concerned, and to permit the admission of fuel oil to the channel means 5 and the circumferential recess 4 to be performed exclusively through the bore 18, until the member 16 has closed the same. The presence, or non-presence, of the bore 9 will consequently be entirely dependent on whether it is desired to permit the portion 21 of the control 50 member 16 to move past the bore 18 for a shorter or longer distance, perhaps with a final limitation of the upward travel of the member 16 by abutment against the face 23. Generally, and on reasons to be understood from the following, 55 it is preferable to maintain the bore 9, however, but is not unavoidably necessary.

When the movement of the control member 16 has been concluded in either of the manners referred to above, the discharge of the fuel 60 oil begins from the pressure chamber 10 through the valve 11. The reason why such discharge has not previously taken place is that the valve 11 is acted upon by the spring 12 and that its area facing the pressure within the cavity 13 is sufficiently greater than the area of the same facing the pressure within the chamber 10.

The pressure within the pressure piping 13, 14, which already is increased by the upward travel of the control member 16 and the compression 70 75 then caused, is now still more increased by the dis-

charge of fuel oil from the pump through the pressure valve 11, and finally the pressure is increased so much that an injection of fuel into the engine cylinder takes place.

During the continuation of the upward stroke of the pump piston 2 after the fuel injection (and in dependence on the fuel consumption in the engine cylinder during the prevailing working stroke) and always before the pump piston has arrived at its upper end position X, a connection is established between the bores 5 and 6 through the circumferential recess 4, and thereby the fuel oil confined within the cavities 4, 5, 20 and 19 will get an opportunity to escape to the suction pipe of the pump. The bore 6 may naturally lead into another low pressure cavity, or even to the atmosphere if desired, instead of leading to the suction piping.

Now, the control member 16 is displaced back into its lower end position shown in the drawing under influence from the pressure within the pressure piping 13, 14, and then said member establishes a connection between the pump pressure chamber 10 and the suction pipe of the pump by means of the bore 18, the recess 19 and the channel means 20, 5, 4 and 6. The discharge of fuel oil into the pressure piping past the valve 11 is not concluded until the control member 16 has uncovered a portion of the cross sectional area of the bore 18, which portion is great enough for permitting escape of the whole amount of fuel oil coming from the pressure chamber 10 during the continued upward movement of the pump piston 2 towards the end position X. Until this moment a discharge successively decreasing in volume will continue through the pressure valve 11.

During its return stroke towards the lower end position, the control member 16 causes an increase of volume of the cavity 13, such volume increase resulting in a decrease of pressure within the pressure piping for prevention of after-dripping in the injection nozzle. This decrease of pressure is delayed to a certain extent, however, by the continued oil discharge through the pressure valve 11, such discharge being interrupted when a sufficiently great portion of the cross sectional area of the bore 18 has been uncovered by the control member 16 only, as stated above. In the pressure piping, the finally decreased pressure remaining until the next working stroke of the fuel pump will therefore be dependent on the magnitude of the continued discharge through the pressure valve 11, and secondarily such magnitude will be dependent on the smaller or greater rapidity of the uncovering of the bore 18 by the member 16. The rapidity of displacement of the member 16 depends in its turn upon the amount of pressure within the pressure piping 13, 14, and this means that in case said pressure is higher, the member 16 will move more rapidly than in case the pressure is lower. In other words, a higher pressure within the pressure piping results in a greater absolute decrease of pressure within the said piping than does a lower pressure therein, and thereby one of the most important results of the invention is obtained.

The absolute decrease of pressure within the pressure piping will therefore adapt itself to the number of revolutions of the engine, as the pressure within said piping will be higher at a higher speed of the engine than at a lower engine speed. The decrease of pressure will also be amplified (which is desirable since the differences in pressure within the pressure piping will be very great at variable number of revolution of the engine) 75

due to the fact that the pump piston 2 will more rapidly establish a communication between the bores 5 and 6 at greater engine speeds than at smaller ones, so that the member 16 will sooner begin its return movement to the lower end position and open the return channel means at the bore 18 at an earlier stage, whereby the continued discharge through the pressure valve 11 will cease more rapidly.

10 When the bore 9 is present, the decrease of pressure may be still more amplified at increased numbers of revolution of the engine when giving this bore an upwardly diverging cross sectional shape and by connecting the upper portion of the same with an annular groove 9' in the cylinder wall, if desired. The suction bore 8 may simultaneously be given an upwardly converging cross sectional area, and both of these arrangements may be understood from Fig. 2 in the drawing.

20 When the fuel pump is provided with a slide valve controlled suction inlet, a greater velocity of the slide valve (in the embodiment shown in the drawing this valve is formed by the pump piston itself) will cause the fuel feeding and the increase of pressure within the pressure chamber 10 caused by such feeding to begin already before the pump piston has closed the suction bore 8 by means of its top face 7, and this being due to a throttle action arising at the suction bore, such throttling action being amplified by the embodiment of the bore 8 just described. This fuel feeding results obviously in that the control member 16 begins its upward travel earlier than in case the speed of travel of the slide valve (piston 2) is lower. On the other hand, the throttle action is retarded at the bore 9 due to its upwardly diverging cross sectional area, and this means that the control member 16 (provided that its movement is not stopped by abutment) will move upwardly to a greater distance at higher than at lower numbers of revolution of the engine, so that a greater increase of volume of the chamber 13 and the pressure piping as a whole will occur at greater than at lower engine speeds, when the said member 16 subsequently returns to its bottom position.

30 The actual decrease of pressure within the pressure piping will be smaller, however, than at first sight is to be supposed when considering the foregoing, and as pointed out above this is due to that the return channel means from the pressure chamber 10 is not opened until the portion 21 of the control member 16 begins to uncover the bore 18. This means that how far the member 16 has ever travelled upwardly in the cylinder bore 15, the decrease of pressure within the pressure piping will always and only correspond to the difference between the volume of fuel oil additionally introduced into the pressure piping 40 through the valve 11, and the amount of volume with which the pressure piping is increased when the control member 16 moves back into a position uncovering the bore 18. This smaller decrease of pressure relatively to the increase of volume of the pressure piping is more advantageous than a decrease of pressure which is directly proportional with the said increase of volume, among others since it causes a pressure reduction process which is extended in respect of time, and this 50 results in a softer, or smoother, pressure reducing process. By means of a suitable dimensioning of the control member 16, it is simultaneously open to provide for that the absolute decrease of pressure will be substantially proportional with the number of revolutions of the en-

gine to the whole range of speeds of the same, so that the pressure remaining within the pressure piping at the intervals between two consecutive fuel injections will be substantially constant.

5 As hinted at in the foregoing, the total amount of fuel fed out from the fuel pump is increased at increasing engine speed, especially if the pump is provided with a slide valve controlled suction intake, and this is due to the throttling coaction between the top face 7 of the pump piston and the suction bore 8, which means that the capacity of the pump is increased with increasing engine speeds, and reduced with decreasing engine speeds. Now, as well known, the actual conditions are that the amount of air sucked in during each working cycle of the engine is decreased with increasing number of revolutions, and increased with decreasing engine speed. Therefore, the maximum capacity of the fuel pump ought to increase with decreasing engine speed, as otherwise the result would be that the engine, when running at low speed and with relatively greater cylinder charge caused thereby, cannot reach its maximum effect otherwise possible, and this is due to a too small admission of fuel oil—a disadvantage which is especially to be noted in engines for vehicles on terra firma for instance when running upgrade. By the construction described in the preceding paragraph the result is obtained that the capacity of the pump is automatically decreased with increasing engine speed, as a greater discharge from the pressure chamber 10 then caused by the throttle action increases the distance of upward travel of the control member 16, and thereby the succeeding increase of volume of the cavity 13 is enlarged, which means a correspondingly reduced volume of injection, as the greater volume of the cavity 13 must be filled again before the next injection can begin.

40 The same results as described in both of the preceding paragraphs may at least approximately be obtained in case the pressure valve, in a manner known per se, is constructed so that it gets an increased working stroke, or distance of elevation from the seat, when the speed of the engine and that of the fuel pump is increased, such increase of the working stroke of the valve being substantially proportional with the increase of the engine speed. This modification has naturally its specific importance when the bore 9 is not at hand. It is easily to be understood that a variable distance of elevation of the pressure valve body will also result in a variable discharge from the pressure pipe through said valve and back to the pressure chamber 10 before the pressure valve has closed. Without additional explanations it is also obvious that this variable return flow will result in effects of the same kind as described above.

50 The pressure valve 11 shown in Fig. 1 is exactly of such a construction that its distance of elevation from the seat is increased with an increasing speed of the pump piston 2. For the purpose, the outflow ports 24 from the pressure valve are assumed to be made so small that they act as throttling means. Hence, with an increasing speed of the pump piston and a more rapid increase of pressure within the pressure chamber 10 and an increased discharge of fuel 60 oil therefrom, a longer period of time will be required until an equalization of pressure has taken place between the valve cavity 13 and the pressure chamber 10. Until this equalization of pressure has been obtained, the raising of the pressure 70

75

valve from its seat will continue. The maximum distance of elevation of the valve 11 may naturally be limited by means of an abutment positioned in any convenient manner.

5 Since the control member 16 must always perform a certain movement towards its lower end position, whereby the volume of the pressure piping is increased, the essential advantage appearing under all working conditions of the engine is that the volumetrical decrease of pressure will always occur previous to the hydrostatical decrease of pressure, which concludes the pressure decreasing process, this advantage being not at hand in connection with the devices previously 10 known for the purpose of causing an increase of volume of the pressure pipe. As will be apparent without explanations, a hydrostatical decrease of pressure cannot take place until a certain portion of the bore 18 has been uncovered, such 15 20 uncovering causing the volumetrical decrease of pressure. This sequence of the steps of the pressure decreasing process results in that the otherwise unavoidable pressure waves which oscillate forth and back within the pressure piping as a 25 continuation of the first pressure wave arising in the direction towards the pressure valve 11 at the closing of the injection nozzle valve, are retarded by a resilient fluid cushion instead of being repelled by a non-resilient wall, as will be the 30 case when the pressure decreasing process is of a volumetrical nature only, or if it is concluded volumetrically, respectively. It is apparent that the aforementioned hydrostatical pressure wave damping effect assists in the rapid elimination 35 of the non-desirable pressure wave oscillations within the pressure piping after conclusion of each fuel injection, and the result in practice is that it is not to be feared that the fuel shall trickle out (after-dripping) through the injection nozzle 40 due to such pressure oscillations, even if the injection nozzle valve should not be perfectly tight.

The constructional embodiment of the apparatus according to the invention may naturally be varied in many ways within the scope of the 45 latter. The construction of the control member may be modified, and the said member and the pressure valve 11 may be mounted one above the other etc. Spring means having a retarding action on the movements and thereby also an influence on the pressure decreasing process and 50 on the control of the volumes may be mounted at one or both sides of the control member 16. Throttle members, or valves, having a retarding influence on the fuel oil flows may be mounted 55 in one or more of the channel means leading to the cylinder 15 for the control member. The circumferential recess 4 and its control edge 3 must not necessarily be provided in the pump piston itself but may be at hand in a separate 60 piston slide, and also in other respects it may be constructively modified or replaced by some common mechanically controlled valve member.

What I claim and desire to secure by Letters Patent is:

65 1. In a fuel feeding means for internal combustion engines, a fuel piston pump for feeding fuel into a pressure piping leading to an injection nozzle of the engine, a control member, a cylinder in which said member is movable, a conduit connecting said cylinder to said pressure piping, a second conduit connecting said cylinder to the pressure chamber of said pump, a third conduit having periodic communication with a low pressure area also connected to said cylinder and 70 75 said control member controlling the communica-

cation between said second and third conduits and being movable in said cylinder by variations in pressure existing in said piping and said pump pressure chamber.

2. In a fuel feeding means for internal combustion engines, a fuel piston pump for feeding fuel into a pressure piping leading to an injection nozzle of the engine, a control member, a cylinder in which said member is movable, a conduit connecting said cylinder to said pressure piping, a second conduit connecting said cylinder to the pressure chamber of said pump, a third conduit connected to said cylinder having communication with a low pressure area, said control member having a port therein adapted to 10 interconnect said second and third conduits, means operated by said pump controlling said third conduit and said control member controlling the communication between said second and third conduits and being movable in said cylinder by variations in pressure existing in said piping and said pump pressure chamber whereby a decrease in pressure within the pressure piping may be secured in accordance with the pressure conditions prevailing therein. 15 20 25

3. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area and a control member movable in said cylinder in response to 30 35 pressure conditions existing in said pressure piping and said pressure chamber.

4. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting 40 45 said cylinder to a low pressure area, a control member movable in said cylinder in response to pressure conditions existing in said pressure piping and said pressure chamber, and said piston controlling said third conduit in accordance with the reciprocations of said pump. 50

5. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to 55 60 pressure conditions existing in said pressure piping and said pressure chamber and a slide valve operated by said pump controlling said third conduit.

6. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to 70 75 80 85 90 95 98 pressure conditions existing in said pressure piping and said pressure chamber.

sure conditions existing in said pressure piping and said pressure chamber, a slide valve operated by said pump controlling said third conduit and a port in said control member interconnecting 5 said second and third conduits during a portion of said control member's movements.

7. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to pressure conditions existing in said pressure piping and said pressure chamber, a slide valve operated by said pump controlling said third conduit and 10 a port in said control member interconnecting said second and third conduits when said control member has been moved by the pressure existing 15 in said pressure piping in order to connect said pressure chamber with said low pressure area at 20 the conclusion of the fuel injection.

8. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member 25 movable in said cylinder in response to pressure conditions existing in said pressure piping and said pressure chamber, means controlling said third conduit periodically in synchronism with said pump and means on said control member for 30 closing said second conduit shortly after the start 35 of the compression stroke of said pump.

9. In a fuel feeding means for internal combustion engines, a fuel piston pump for feeding fuel into a pressure piping leading to an injection 45 nozzle of the engine, a pressure chamber for said pump, a conduit connecting said chamber to said pressure piping, means connecting said chamber with a low pressure area and means operative by the pressure in said chamber for closing said 50 means connecting said chamber with a low pressure area.

10. In a fuel feeding means for internal combustion engines, a fuel piston pump for feeding fuel into a pressure piping leading to an injection 55 nozzle of the engine, a pressure chamber for said pump, a conduit connecting said chamber to said pressure piping, means connecting said chamber with a low pressure area and means operative by the pressure in said chamber for closing said 60 means connecting said chamber with a low pressure area, and then reopening the same upon the conclusion of the fuel injection.

11. In a fuel feeding means for internal combustion engines, a fuel piston pump having a 65 pressure chamber, a duct leading from said chamber to the pressure piping leading to an injection nozzle of an engine, a cylinder, a conduit connecting said cylinder to said pressure piping, a second conduit connecting said cylinder and said pressure 70 chamber, a third conduit connecting said cylinder to a low pressure area, a control member movable in said cylinder in response to pressure conditions existing in said pressure piping and said pressure chamber, a groove provided in the outer 75 face of said control member, said groove being

adapted upon movements of said control member to be brought into and out of register with said second conduit and said control member having a passage connecting said groove with said third conduit.

5

12. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to pressure conditions existing in said pressure piping and said pressure chamber, a fourth conduit connecting said pressure chamber with said cylinder and said fourth conduit having permanent communication with said third conduit and adapted to be closed when the pump has travelled a certain distance at the beginning 15 of its working stroke.

15

13. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to pressure conditions existing in said pressure piping and said pressure chamber, means for periodically closing said third conduit to disconnect said cylinder from said low pressure area, a fourth conduit interconnecting said pressure chamber and said cylinder, said fourth conduit communicating at all times with said 30 third conduit and adapted to be closed by said pump piston when said pump piston has travelled a certain distance at the beginning of its working stroke, and said fourth conduit being so positioned and dimensioned that before being 35 closed by said pump piston a sufficiently great quantity of fuel oil will have passed therethrough for causing a displacement of said control member a longer distance than needed for moving said control member in order to disconnect said 40 third conduit and adapted to be closed by said pump piston when said pump piston has travelled a certain distance at the beginning of its working stroke, and said fourth conduit being so positioned and dimensioned that before being 45 closed by said pump piston a sufficiently great quantity of fuel oil will have passed therethrough for causing a displacement of said control member a longer distance than needed for moving said control member in order to disconnect said 50 second and third conduits.

50

14. In a fuel feeding means for internal combustion engines, a fuel piston pump having a pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to pressure conditions existing in said pressure piping and said pressure chamber, means for periodically closing said third conduit from said low pressure area and opening the same at the 65 conclusion of the fuel injection, a groove provided in said control member adapted upon movement of said control member to be brought into and out of connection with said second conduit, a port interconnecting said groove and said 70 third conduit, a fourth conduit interconnecting said pressure chamber and said cylinder and being in permanent communication with said third conduit, said fourth conduit being so located that it is closed by the pump piston when it has 75

- travelled a certain distance at the begining of its working stroke and the opening of said fourth conduit into said pressure chamber having a cross sectional area diverging in the direction of the working stroke of the pump piston.
15. In a fuel feeding means as set forth in claim 14, a suction intake for the pressure chamber of said pump which is adapted to be opened and closed by the movements of the pump piston, 10 said intake having a cross sectional area converging in the direction of the working stroke of the pump piston and said intake being so positioned as to be completely closed by the piston slightly previous to the complete closing of said 15 fourth conduit by said pump piston.
16. In a fuel feeding means for internal combustion engines, a fuel piston pump having a

pressure chamber, a duct leading from said chamber to the pressure piping leading to an injection nozzle of an engine, a cylinder, a conduit connecting said cylinder to said pressure piping, a second conduit connecting said cylinder and said pressure chamber, a third conduit connecting said cylinder to a low pressure area, a control member movable in said cylinder in response to pressure conditions existing in said pressure piping and said pressure chamber, a 10 pressure valve provided in said duct, a seat therefor and said pressure valve being so constructed that its distance of elevation from said seat is increased with an increase of the speed of the fuel piston pump. 5

CARL HERMAN CLAUSEN. 15
